SNAP ACTION SWITCH

George M. Hausler, Schenectady, N. Y., assignor to General Electric Company, a corporation of New York

Application July 16, 1954, Serial No. 443,823

7 Claims. (Cl. 200—67)

This invention relates to improvements in electrical switches and more particularly to that type of electrical switch having a snap action operating characteristic.

An electric switch is frequently required to operate with rapid and positive contact movement although controlled by an actuating means, such as a pressure, fluid level or temperature responsive device, which travels only through a small distance at a very slow rate. To prevent an undesirable condition of contact arcing, it is desirable to provide a switch in which a high contact pressure will be maintained up to the moment of operation whereupon the switch contacts will open or close with a snap action.

Accordingly, it is an object of my invention to provide an improved electrical switch having a mechanism in which irreversible motion is initiated by an actuating means before positive contact pressure is reduced to zero whereupon snap operation occurs regardless of the distance or rate of movement of the actuating means.

It is a further object of my invention to provide an improved snap action switch with a minimum number of operating parts which is small in size, inexpensive to manufacture, yet durable, reliable and highly sensitive.

A still further object of my invention is to provide a snap action switch with a simplified mechanism particularly well suited for double pole, single throw switching applications.

Another object of my invention is to provide a snap action switch operated by a movable actuating means wherein the switch is readily and conveniently changeable from a switch with normally open contacts to a switch with normally closed contacts, and vice versa.

In carrying out my invention in one form, I utilize a movable switch member formed at least in part of resilient spring material. Such switch member comprises a pair of resilient outer tension arms disposed in flatwise coplanar parallel spaced apart relation and fixedly mounted at like ends, a pair of compression arms in intermediate parallel spaced apart relation each flexibility connected for relative pivotal movement at one end to a free end of one outer tension arm and joined together at their other ends, and a parallel central tension arm connected at one end to the junction of the compression arms. This central tension arm may be an integral part of the switch member and hereafter will be referred to as a part thereof, but it is preferably a separate tension spring. A movable switch contact is mounted on the free end of each outer tension arm in cooperating relationship with one of a pair of stationary switch contacts. The portion of the switch member interconnecting the compression arms is preferably of insulating material to electrically isolate the two movable switch contacts thereby rendering the switch suitable for double pole application.

An actuating member is connected to the outer end of the central tension arm and is movable in a transverse path to carry the tension centerline of the central tension arm across the compression centerline of the com-

2

pression arms at which point the interconnecting portion will snap from one to the other of two preselected positions. This snap action will cause the compression centerline of the compression arms to cross the tension centerline of the outer tension arms at which point the free ends of the outer tension arms will move with snap action from one to the other of two preselected positions, one of which is defined by the stationary switch contacts. Thus, the movable switch contacts are carried with a snap action into or out of engagement with the stationary switch contacts independently of the rate of movement of the actuating member.

The movable switch member is located approximately on the centerline of an enclosure, and the enclosure is suitable for mounting with its cover facing either up or down with respect to the actuating member. Therefore, it is possible to mount the enclosure in alternate positions whereby the switch contacts will be either normally open or normally closed as desired.

My invention will be better understood and further objects and advantages will be apparent from the following detailed description taken in conjunction with the accompanying drawing, in which Fig. 1 is an overall elevational view of the enclosure for my improved snap action switch mechanism; Fig. 2 is a plan view of the switch mechanism shown with the enclosing cover removed; Fig. 3 is an elevational view of the switch enclosure with the near side broken away to more clearly indicate the positions of switch components with the switch contacts closed; and Fig. 4 is another elevational view similar to Fig. 3 except with the switch contacts in their open position.

Referring now to Fig. 1, an enclosure 11 comprising a cover 12 and a base 13 provides a housing for the snap action switch mechanism of my invention. A pair of holes 14 are provided through enclosure 11 and accommodate bolts (not shown) which fasten the cover 12 to the base 13 and also fasten the enclosure 11 to a suitable supporting frame (not shown). The enclosure 11, is constructed preferably of a molded plastic insulating material.

As shown in Fig. 2, the snap action switch mechanism mounted inside enclosure 11 comprises a thin, flat movable switch member 15, a pair of fixed switch contacts 17, and suitable clamping type terminals 18 for terminating four electrical connectors (not shown) entering enclosure 11 from a remote circuit to be controlled by the switch. A pair of cooperating movable switch contacts 16 are carried by switch member 15.

Each terminal 18 comprises an I-shaped post 19, a clamping member 20 encircling the post 19 and a clamping screw 21, as shown in the drawing. Each post 19 extends in a transverse direction. A pair of holes 22, one in cover 12 and one in base 13, is associated with each post, each hole being located so that an electrical conductor entering enclosure 11 through the hole will extend parallel to and immediately adjacent one surface of the associated post 19. The clamping member 20 encircles not only the post 19 but also the conductor, and by means of the clamping screw 21 which is threaded through the clamping member 20 to engage the opposite surface of post 19, the clamping member 20 can be tightened to clamp the conductor against the post. An aperture 23 is provided in enclosure 11 opposite the head of each screw 21 whereby the clamping type terminal 18 may be tightened or loosened without the necessity of removing cover 12.

Each fixed switch contact 17 is mounted on base 13 by means of a pair of rivets 24 and is connected to a terminal 18 having the construction described above.

To obtain snap action, the movable switch member 15 is comprised of a plurality of substantially parallel

spaced apart elongated arms of which three are tension arms and two are compression arms. A pair of outside arms 25, longitudinally stressed in tension, are constructed of suitable strips of current conducting, resilient material. A fixed end 26 of each arm 25 is anchored to base 13 by a rivet 27, and a connection is made at this end to a terminal 18 having the construction described above. Due to the resiliency of arm 25, the other end 28 of each outside tension arm 25 is free to move in a transverse direction pivotally about the fixed end 26. From free end 28 a portion of the resilient strip is disposed parallel to arm 25 on its inward side, and the resulting U configuration forms a flexible connection 29.

The movable switch contacts 16 are mounted on the outside tension arms 25 of the movable switch member 15. Each contact 16 is located at the free end 28 of an arm 25 where it faces a stationary contact 17 in contact making and breaking relation. Clockwise pivotal movement of the free end 28 of arm 25 about fixed end 26, as viewed in Fig. 3, will carry contact 16 into engagement with contact 17. Stationary contact 17 thereby serves as a stop for the free end 28 when moved in this direction. Upon counterclockwise pivotal motion of the free end 28, the cooperating contacts 16 and 17 will disengage. As can be seen in Fig. 4, a stop 30 formed by a protrusion of cover 12 engages connection 29 to stop the counterclockwise movement of free end 28. Operation of the switch mechanism will open and close the remote electrical circuit connected to cooperating movable and stationary switch contacts by means of the terminals 18 connected respectively to the fixed end 26 of tension arm 25 and to the stationary contact 17.

Two intermediate arms 31 longitudinally stressed in compression are disposed inwardly adjacent to the two outside tension arms 25. Each arm 31 is formed from a different leg of a unitary U-shaped strip of insulating material 32. The open end of each leg is connected by a pair of rivets 33 to the inwardly disposed end of a different resilient strip 25. A closed end portion 34 of each leg is free to move in a transverse direction pivotally about the flexible connection 29 formed at free end 28 of each outside tension arm 25. To limit the movement of end 34 of each compression arm 31, two pairs of stops, 35 and 36, are formed by projecting portions of the cover 12 and base 13, respectively, and are disposed on opposite sides of the ends 34, as shown in Figs. 3 and 4.

To insure that both movable switch contacts 16 operate in unison to make and break contact with the stationary switch contacts 17 substantially simultaneously, the unitary U-shaped strip 32 comprising part of both compression arms 31 is constructed of relatively rigid material. Thus the flexible connections 29 formed at the free ends 28 of both outside tension arms 25 are rigidly interconnected, and movement of one will be translated to corresponding movement of the other.

The double pole construction of my snap action switch is a result of the insulating characteristic of the unitary strip 32. This interconnecting member electrically insulates one outside tension arm from the other outside tension arm and thereby insulates connections made to one movable switch contact 16 and its cooperating stationary switch contact 17 from connections made to the other movable and stationary switch contacts.

A first snap action system is formed by the coaction of an intermediate compression arm 31 and an outside tension arm 25. The stress arm 25 in tension. Whenever the centerlines of the forces in these two arms are in alignment, the compression and tension forces are equal and opposite and all of the compression force is used to stress the tension arm. However, when the centerline of these two forces are not aligned, the compression force is opposed at flexible connection 29 by an equal force having two components; a longitudinal component in the plane of arm 25 stressing this tension arm, and a transverse component perpendicular to the plane of tension

arm 25 applying a torque at 29, with tension arm 25 forming the moment arm, tending to pivot the connection 29 about the fixed end 26 of arm 25. Thus, as shown in Fig. 3, with end 34 of compression arm 31 above the tension centerline of tension arm 25, a transverse component of force at connection 29 applies a positive pressure to hold movable contact 16 in engagement with stationary contact 17. Should compression arm 31 be pivoted counterclockwise about the flexible connection 29, the compression centerline of arm 31 will cross the tension centerline of arm 25 whereupon the component of transverse force at 29 will pass through zero and change direction to move connection 29 with a snap action counterclockwise about fixed end 26 of arm 25 to its upper position determined by engagement with stop 36, shown in Fig. 4.

To control the movement of the closed end portion 34 of each compression arm 31, a third tension arm 37 is provided. One end of tension arm 37 is pivotally connected to a mid-portion 38 of the closed end of the U-shaped strip 32 interconnecting the pair of compression arms 31. In the illustrated embodiment of my invention this central tension arm of the movable switch member comprises a tension spring. The other end 39 of central tension arm 37 is adapted to be connected to an actuating means. The actuating means is movable in a transverse path and supplies a sufficient force to longitudinally stress central arm 37 in tension. Although the actuating means may be of any suitable type, for the purposes of this specification it has been illustrated in Fig. 1 as comprising an L-shaped rigid actuating member 40 pivotally connected at one end to a fixed pivot 41. The other end 42 is connected to end 39 of the central tension arm 37. A pair of fixed stop pins 43 and 44 define the upper and lower limits respectively of the transverse travel of the actuating member 40, and a bias spring 45 normally biases the member 40 to its lower position. A plunger 46 acts against the force of the bias spring 45 to pivotally move member 40 to its upper position. Plunger 46 may be operated by any suitable means, such as, for example, a pressure responsive diaphragm, not shown; and it will be assumed that its rate of movement is exceptionally slow. The force in the central tension arm 37, as supplied by the tension spring 40 in combination with the actuating means, provides the source of force for the entire movable switch member 15 to stress both the compression arms 31 and the outside tension arms 25.

A second snap action system is formed by the coaction of the central tension arm 37 and a compression arm 31. The tension arm 37 supplies a force at the pivotal connection 38 to stress arm 31 in compression. Whenever the centerlines of the forces in these two arms are in alignment, the tension and compression forces are equal and opposite and all of the tension force is used to compress arm 31. However, whenever the centerlines of these two forces are not in alignment, the tension force is opposed at connection 38 by an equal force having two components; a longitudinal component in the plane of arm 31 stressing this compression arm, and a transverse component perpendicular to the plane of the compression arm 31 applying a torque at connection 38, compression arm 31 forming the moment arm, tending to pivot connection 38 about the flexible connection 29. Thus, as shown in Fig. 3, with end 39 of central tension arm 37 above the compression centerline of compression arm 31, a transverse component of force at pivotal connection 38 positively holds the closed end 34 of compression arm 31 in its upper position determined by engagement with stop 35. By lowering the actuating member 40, the tension centerline of arm 37 will pass through a position of alignment with the compression centerline of arm 31 in which position the component of transverse force at connection 38 will pass through zero and change direction to urge the closed end 34 of arm 31 counter-

clockwise about flexible connection 29 with a snap action to its lower position as determined by engagement with stop 36, shown in Fig. 4.

In effect, the movable switch member 15 described above comprises a pair of flat integral U-shaped strips of resilient material having a long and a short arm and arranged on coplanar side by side relation with the short arms 31 disposed inwardly and interconnected at their open ends. The outer arms 25 are fixedly mounted at their open ends. A spring means 37 is connected to the common ends of the inner arms to place the inner arms in compression and the outer arms in tension thereby to provide separate overcenter operation of the inner arms with respect to the spring means and with respect to the outer arms.

Movement of the actuating member 40, as controlled by movement of plunger 46, may be very slow. However, it need only carry end 39 of central tension arm 37 through a well defined position in which the tension centerline of arm 37 crosses the compression centerline of compression arms 31 to produce a snap action opening or closing of switch contacts 16 and 17. Upon reaching this position of alignment, the closed end portions 34 of compression arms 31 will snap from one to the other of their alternate positions defined by stops 35 and 36, as described above for the second snap action system. As a result, compression arms 31 will pass through a position wherein their compression centerline is in alignment with the tension centerline of the outside tension arms 25, and the flexible connections 29 will snap from one to the other of their alternate positions defined by stops 30 and stationary contacts 17, as described above for the first snap action system. This sequence of snap actions takes place extremely fast and is irreversible. The former must be underway before the latter can occur. Therefore, the position of the movable switch contacts 16 will be maintained with positive pressure until after the former snap action has been initiated. The actuating member 40, having initiated the former snap action, can exercise no further control over the switch mechanism until after the sequence of snap actions has been completed.

Contact bounce is substantially eliminated in this snap action switch. Whenever the free end 28 of each outside tension arm 25 is in either of its alternate positions as defined by the engagement of contacts 16 and 17 or by connection 29 engaging stop 30, a transverse component of force is present to apply a positive pressure to hold free end 28 in that position. This transverse force, together with the low inertia of small and light weight moving parts, enables the switch mechanism to operate with substantially no contact bounce. Similarly, there is substantially no bounce at the closed end 34 of each compression arm 31 upon operation thereof.

To enable the double pole snap action switch to be operated as either a normally open or normally closed switch, the location of the switch mechanism inside enclosure 11 is carefully selected so that the position of the plane of the movable switch member 15, when in an unstressed condition, will correspond approximately with the centerline of the enclosure 11. With the enclosure 11 located as shown in the drawing, and the actuating member 40 normally biased to its lower position, the switch contacts 16 and 17 will be normally open, as illustrated in Fig. 4. Upward movement of the actuating member 40 will cause movable switch contact 16 to snap into engagement with the stationary switch contact 17. However, it is possible to turn over the enclosure 11 and mount it with cover 12 down, base 13 up. In this position, not shown, the normally biased downward actuating member 40 will result in normally closed switch contacts 16 and 17, and upward movement of member 40 will cause the movable switch contact 16 to snap out of engagement with stationary contact 17. It is a relatively easy matter to reverse the position of the enclosure

11. Electrical connectors entering enclosure 11 through holes 22 in cover 12, for example, and clamped to terminals 18 can be loosened and removed while the enclosure 11 is reversed, after which they can be reinserted through holes 22 in the base 13 and reclamped.

While I have shown and described a preferred form of my invention by way of illustration, many modifications will occur to those skilled in the art. I therefore contemplate by the appended claims to cover all such modifications as fall within the true spirit and scope of my invention.

What I claim as new and desire to secure by Letters Patent of the United States is:

1. A snap action switch comprising a pair of parallel spaced apart elongated compression arms each having opposite first and second end portions which are movable in a transverse direction, relatively rigid means interconnecting the first end portions of said compression arms, first and second parallel spaced apart tension arms disposed laterally adjacent said compression arms and each including a resilient elongated portion having one end flexibly connected to the second end portion of one of said compression arms and having the other end fixedly mounted, each of said first and second tension arms forming a snap action system with the associated flexibly connected compression arm, whereby the second end portions of said compression arms will move with snap action whenever the compression centerline of said compression arms is moved through a position of alignment with the tension centerline of said first and second tension members in response to transverse movement of said interconnecting means, a third elongated tension arm disposed intermediate and in parallel relationship to said compression arms and having one end movable in a transverse direction and the other end pivotally connected to said interconnecting means to form with said compression arms another snap action system, whereby said interconnecting means will move with snap action whenever the tension centerline of said third tension arm is moved through a position of alignment with the compression centerline of said compression arms in response to transverse movement of said one end of said third tension arm, a movable actuating member connected to said one end of said third tension arm and disposed to apply tensile stress to said third tension arm while moving in a transverse path thereby to actuate the snap action systems, a pair of movable switch contacts mounted for movement with the second end portions of said compression arms, and a pair of stationary switch contacts fixedly mounted in cooperating relationship with said movable switch contacts.

2. A snap action switch comprising a thin, flat movable switch member having an outer pair of substantially parallel tension members each having a resilient longitudinal portion extending between a fixed end and a free end, a pair of intermediate parallel compression members each having one end pivotally connected to a different said free end, means interconnecting the other ends of both said compression members, and a central parallel tension member having one end pivotally connected to said interconnecting means; a movable actuating member connected to the other end of said central tension member and disposed to apply tensile stress to said central tension member while moving in a path substantially perpendicular to the plane of said movable switch member; a pair of movable switch contacts supported by said switch member near said free ends and movable with snap action in a direction substantially perpendicular to the plane of said movable switch member in response to movement of the tension centerline of said central tension member through a position of alignment with the compression centerline of said pair of compression members; and a pair of spaced apart stationary switch contacts fixedly mounted in cooperating relationship with said movable switch contacts.

3. A snap action switch comprising a stationary support member, a thin, flat movable switch member having a plurality of substantially parallel spaced apart interconnected elongated arms including three tension arms and a pair of intermediate compression arms, a relatively rigid insulating member interconnecting like ends of said compression arms, an outside pair of said tension arms each having a resilient elongated portion with a fixed end mounted on said support member and a free end flexibly connected to the end of the adjacent compression arm opposite said interconnected end and movable in a transverse direction between two preselected positions, a pair of movable switch contacts each mounted on said switch member near a different said free end, a pair of spaced apart fixed switch contacts mounted on said support member in cooperating relationship with said movable switch contacts, first and second stops mounted on said support member in spaced apart relation opposing said pair of fixed switch contacts to define therewith said preselected positions of said free end, said outside tension arms and said compression arms forming a first snap action system actuated by transverse movement of said insulating member to move the compression centerline of said compression arms through a position of alignment with the tension centerline of said outside tension arms whereupon said free end will snap from one to the other said preselected positions, third and fourth opposing stops mounted on said support member in spaced apart relation on opposite sides of said insulating member to limit the transverse travel thereof, a central said tension arm having one end pivotally connected to said insulating member and forming with said compression arms a second snap action system actuated by transverse movement of the other end of said central tension arm to move the tension centerline of said central tension arm through a position of alignment with the compression centerline of the compression arms whereupon said insulating member will move with snap action between said opposing stops, and a movable actuating member connected to said other end of said central tension arm and movable in a transverse path to apply tension to said central tension arm and to move said central tension arm thereby to actuate said second snap action system whereupon said first snap action system will operate.

4. A snap action switch comprising an enclosure having a height defined by opposing substantially flat parallel top and bottom surfaces, a movable switch member located within said enclosure having a plurality of parallel spaced apart interconnected tension and compression members generally defining a plane parallel to said top and bottom surfaces, a first said tension member having a resilient longitudinal portion with a fixed end connected to said enclosure and a free end movable in a transverse direction, a movable switch contact supported by said switch member near said free end of said first tension member, a fixed switch contact mounted in said enclosure in cooperating relationship with said movable switch contact, a said compression member having one end pivotally connected to said free end of said first tension member, a second tension member having one end pivotally connected to the opposite end of said compression member, and a biased movable actuating member releasably connected to the opposite end of said second tension member in tension applying relationship and movable against its bias in a transverse path to move the tension centerline of said second tension member through a position of alignment with the compression centerline of said compression member thereby to actuate snap action of said free end to carry said movable contact into or out of engagement with said fixed contact, said position of alignment approximately bisecting the height of said enclosure between said top and bottom surfaces to permit the reversing of the direction of snap movement

of said movable switch contact in response to movement of said actuating member against its bias by reversing said top and bottom surfaces with respect to said actuating member.

5. In a snap action electric switch, a movable switch member comprising a pair of flat integral U-shaped strips of resilient material disposed in coplanar side by side relation to provide inner and outer pairs of arms, means interconnecting said pair of inner arms at their open ends, means fixedly mounting said switch member at the open ends of said pair of outer arms, spring means connected to the interconnected ends of said inner arms to place said inner arms in compression and said outer arms in tension thereby to provide separate overcenter operations of said inner arms with respect to said spring means and with respect to said outer arms, and a movable switch contact mounted upon said switch member near the bight of at least one said U-shaped strip.

6. In a snap action electric switch, a movable switch member comprising a pair of flat integral U-shaped strips of resilient material disposed in coplanar side by side relation to provide inner and outer pairs of arms, insulating means physically interconnecting but electrically isolating said pair of inner arms at their open ends, means fixedly mounting said switch member at the open ends of said pair of outer arms, spring means connected to the interconnected ends of said inner arms to place said inner arms in compression and said outer arms in tension thereby to provide separate overcenter operations of said inner arms with respect to said spring means and with respect to said outer arms, a pair of spaced apart movable switch contacts mounted upon said switch member near the bights of said U-shaped strips, and a pair of stationary switch contacts fixedly mounted in cooperating relationship with said movable switch contacts.

7. In a snap action electric switch, an enclosure having a height defined by substantially flat parallel top and bottom surfaces, a movable switch member located within said enclosure and comprising a pair of flat integral U-shaped strips of resilient material disposed in coplanar side by side relation to define generally a plane parallel to and equidistant between said top and bottom surfaces and to provide inner and outer pairs of arms, means interconnecting said pair of inner arms at their open ends, means fixedly mounting said switch member in said enclosure at the open ends of said pair of outer arms, a movable elongated member connected to the interconnected ends of said inner arms and disposed in parallel relation between said inner arms, actuating means connected to said elongated member for supplying a force to stress said elongated member and outer arms in tension and said inner arms in compression, said actuating means being movable in a transverse direction to initiate separate overcenter operations of said inner arms with respect to said elongated member and with respect to said outer arms, at least one stationary switch contact mounted in said enclosure, and a cooperating movable switch contact mounted upon said switch member near the bight of at least one said U-shaped strip for snap action movement into or out of engagement with said fixed switch contact, the direction of movement of said movable switch contact in response to movement of said actuating means in a given direction being selectable by locating said enclosure in alternate, reversed positions with respect to the given direction of movement of said actuating means.
